INVENTOR

BY

John T. Knott

H. G. Burns ATTORNEY

UNITED STATES PATENT OFFICE.

JOHN T. KNOTT, OF PERU, INDIANA.

LAUNDRY-TRAY FAUCET.

Application filed August 25, 1924, Serial No. 733,909.

To all whom it may concern:

Be it known that I, JOHN T. KNOTT, a citizen of the United States of America, and resident of Peru, in the county of Miami 5 and State of Indiana, have invented certain new and useful Improvements in Laundry-Tray Faucets, of which the following is a specification.

This invention relates to improvements in laundry tray faucets especially of the twin type for controlling the flow from separate supply pipes and discharging through a common spout. The object of the invention is to provide a mount in connection with 10 the body of the faucet for securing it firmly upon a laundry tray and to insure its proper and permanent alinement thereon. And another object is to provide a means for sustaining the faucet in its permanent position 15 upon the laundry tray at the time of its installation prior to its connection with the supply pipes.

These objects are accomplished by the construction illustrated in the accompanying 20 drawings, in which:—

Fig. 1 is a front elevation of a faucet embodying the invention shown in position on a laundry tray, a portion of which is in section;

Fig. 2 is a side elevation of the same, a portion being shown broken away; and

Fig. 3 is a fragmentary rear view showing one of the legs of the faucet body and its movable jaw.

The characters appearing in the description refer to parts shown in the drawings and designated thereon by corresponding characters.

The invention comprises a hollow manifold or faucet body 1 with separate connections 2 and 3 for corresponding supply pipes 4 and 5, and having also faucet members 6 and 7 for controlling the flow of water passing through the manifold from the supply 40 pipes respectively. The manifold has also a connection 8 for a swinging spout 9 for the discharge of water admitted through the faucet members. The manifold has a pair of integral legs 10 spaced apart and positioned so that the discharge connection 8 extends midway therebetween. Each leg 10 has a foot 11 that extends forward and which has a pendant portion forming a jaw 12, there being side walls 20 for resting on 45 the top of the wall 14 of the laundry tray 15,

Said foot has a chamber 16 therein that is opened through the rear thereof, and a movable jaw 17 is provided with an overhanging extension 18 that has sliding relation with the foot in the chamber therein, there being a screw 19 extending loosely through the front of the foot and into the extension with which it has threaded relation. The sides of the extension 18 fit snugly between the side walls 20 of the foot and is guided thereby and held closely alined in position in the chamber. The jaws 12 and 17 are positioned oppositely with the back wall 14 of the tray extending therebetween, and when the screw 19 is tightened the jaws are drawn toward each other and clamped firmly upon the back of the tray. In this manner the manifold or faucet body is rigidly positioned in connection with the tray.

The side walls of the feet are disposed in planes parallel with each other, and the extensions on the movable jaws alined respectively in said feet are movable in planes parallel with each other, which assures proper seating of the feet and jaws when the jaws are clamped in place upon the back of the tray.

Another feature of the invention is the chambered feet having side walls which rest firmly upon the top of the tray while the extensions on the movable jaws rest also upon the top of the tray and are confined in proper alinement with the feet between the side walls thereof. The extensions of the movable jaws being concealed within the feet of the legs and being located at the back thereof leaves the front of the leg structure smooth and without objectionable obstructions, and besides a neat appearance of the exposed front parts is effected.

In utilizing the invention, the movable jaws are assembled and held loosely in their respective positions in the corresponding feet by their screws and when the faucet is installed it is only necessary to set the jaws astride the back wall of the tray and tighten the screws. In this manner is eliminated more or less of the labor and the time required for installation when devices of usual construction are employed.

What I claim is:—

1. In a faucet, a faucet body having integral legs spaced apart each having a foot with side walls and a pendant jaw, there being a chamber form in the foot by said

walls and opening through the back thereof; a movable jaw for each foot having an overhanging extension positioned in the chamber of the foot and held alined therein between the side walls of the foot; and a screw extending through the front of each foot and into the extension of the corresponding movable jaw.

2. In a faucet for a laundry tray, a faucet body formed with a pair of spaced integral legs, each having a foot and a pendant jaw at its front, said foot having a chamber therein that opens through its back; and a clamping means including a pendant jaw having an overhanging extension at its top that is positioned in the chamber of the foot and a screw for each foot extending through the front thereof and having threaded relation with the extension.

3. In a faucet for a laundry tray, a faucet body including a pair of spaced integral legs, each having a foot with a pendant jaw and side walls; a pair of movable jaws, each

having an overhanging extension movably positioned between the side walls of the corresponding foot, said side walls and said extensions being disposed in parallel planes; and a screw extending through the front of each foot and engaging the corresponding extension therein.

4. In a faucet for a laundry tray, a faucet body including a pair of spaced feet each having a pendant jaw at its front and a rearwardly extending chamber; and a clamping means including a pair of movable jaws, each having an overhanging extension positioned in the chamber of the corresponding foot and restricted to longitudinal movement in parallelism with the other movable jaw.

In testimony whereof I affix my signature in presence of two witnesses.

JOHN T. KNOTT.
